US00D478006S

(12) **United States Design Patent** (10) Patent No.: **US D478,006 S**
 Smith et al. (45) Date of Patent: ** Aug. 5, 2003

(54) **RECLOSABLE CONTAINER LID**

(75) Inventors: **Stephen Alan Smith**, Naperville, IL (US); **Warren Giles Wiedmeyer**, Trevor, WI (US); **John Stewart Gitschlag**, Chicago, IL (US); **James Tam Joines, Jr.**, Gurnee, IL (US); **Bryce G. Rutter**, St. Louis, MO (US); **Brian C. Bone**, St. Louis, MO (US)

(73) Assignee: **Solo Cup Company**, Highland Park, IL (US)

(**) Term: **14 Years**

(21) Appl. No.: **29/165,203**

(22) Filed: **Aug. 5, 2002**

Related U.S. Application Data

(63) Continuation-in-part of application No. 09/923,763, filed on Aug. 6, 2001.

CLAIM

The ornamental Design for a reclosable container lid, as shown and described.

DESCRIPTION

FIG. 1 is a perspective view of a reclosable container lid of the invention;

FIG. 2 is a side view of the reclosable container lid of FIG. 1;

FIG. 3 is a side view of the reclosable container lid of FIG. 1;

FIG. 4 is a side view of the reclosable container lid of FIG. 1; and,

FIG. 5 is a top view of the reclosable container lid of FIG. 1.

The broken lines in the Figures form no part of the claimed design.
